WILLIAM C. LANG, OF CLEVELAND, OHIO.

FIRE-HOSE CART.

1,127,029.

Specification of Letters Patent.

Patented Feb. 2, 1915.

Application filed March 29, 1913. Serial No. 757,486.

To all whom it may concern:

Be it known that I, WILLIAM C. LANG, a citizen of the United States of America, residing at Cleveland, in the county of Cuyahoga and State of Ohio, have invented certain new and useful Improvements in Fire-Hose Carts; and I hereby declare the following to be a full, clear, and exact description of the invention, such as will enable others skilled in the art to which it pertains to make and use the same.

This invention relates to improvements in fire-hose-carts.

The primary object of this invention is to inflate the hose of a fire-hose-cart while connected with the hose-winding drum of the cart and keep the hose inflated when the hose is not in use, and thereby cause the hose to be kept in a sound condition and ready for use without liability, when used at a fire, of bursting which would be liable to result from cracking or mutilation of the hose if the hose were permitted to become flattened or bent when not in use.

Another object is not only to provide a fire-hose-cart with a winding drum for winding up and paying out the fire-hose of the cart, but to have said drum provided internally with a chamber in which compressed air is stored, to conduct air under pressure into said chamber at the axis of the drum, to control the passage of air to said chamber, to conduct air under pressure from said chamber to the fire-hose connected to the drum, to control the passage of air from said chamber to the hose, to indicate the pressure of air in said chamber, and to indicate the pressure of air in the hose.

With these objects in view, and to the end of realizing any other advantages hereinafter appearing, this invention consists in certain features of construction, and combinations and relative arrangement of parts, hereinafter described, pointed out in the claims, and illustrated in the accompanying drawings.

In said drawings, Figure 1 is a side view of a fire-hose-cart embodying my invention. Fig. 2 is a vertical section on line 2—2, Fig. 1, looking in the direction indicated by the arrow. Fig. 3 is a section on line 3—3, Fig.

2, looking outwardly. Fig. 4 is a section on line 4—4, Fig. 2, looking outwardly. Fig. 5 is a top plan of a portion of but drawn on a larger scale than Fig. 1, and portions are broken away and in section in Fig. 5 to more clearly show the construction.

Referring to said drawings, A indicates two suitably supported laterally spaced side frames of a fire-hose-cart, and B represents a winding drum employed in winding up or paying out fire-hose C which is shown as not in use and therefore wound on the drum. The drum is arranged horizontally between the frames A. The drum is provided with two trunnions D and E arranged horizontally at opposite ends respectively of and centrally of the drum and in line endwise. Said trunnions have bearing in the frames A. The trunnion D is solid and is shown operatively provided with a wheel d for rotating the drum. The trunnion E is tubular, having a bore e which extends longitudinally of the trunnion and is in communication at its inner end, as at e', with a chamber b formed interiorly of the drum B, and said trunnion E is provided with a valve f for controlling the passage of air through the said bore. Obviously upon placing the trunnion E at its outer end in communication with an air-pump (not shown) and operating said pump upon opening the valve f air under pressure is supplied to the chamber b. It will be observed therefore that the bore e in the trunnion E forms the air-inlet of the chamber b.

The drum B is provided with two rails 8 and 8 arranged at opposite ends respectively and extending circumferentially of the drum, and the hose C is shown wound on the drum between said rails.

The drum B is provided at one end at the periphery of the drum and externally of the chamber b with a passageway 10 which is arranged at the periphery of the drum and at the inner side of the adjacent rail 8 and extends circumferentially of the drum, which passageway is in communication, at one end, as at 12, with said chamber and forms the air-outlet of said chamber. Said passageway communicates at its other end with the hose C which has its fluid-receiving

end removably attached in any approved manner, at said end of said passageway, to the drum. The passageway 10 therefore discharges into the drum-communicating end 5 of the hose which is provided at its opposite end with a nozzle 13 having a valve 14 (see Fig. 4) for controlling communication through the nozzle.

Two pressure-gages G and H are placed 10 in communication with the passageway 10 at points spaced longitudinally of the passageway between the point where said passageway discharges into the hose and the point where said passageway communicates 15 with the chamber b; and a suitably applied valve I controls communication through said passageway between the points at which the pressure-gages are placed in communication with the passageway. Each 20 pressure-gage is shown placed in open relation with the passageway 10 by a suitably applied pipe 15. To cause as little interference as possible, by the formation of the passageway 10 at the periphery of the drum, with the hose wound on the drum the outer circumferentially extending wall 16 25 of said passageway (see Fig. 3) gradually approaches the chamber b in the direction in which the drum is rotated in winding up 30 the hose, which direction is indicated by the arrow 17 in Figs. 1, 3 and 5.

By the construction hereinbefore described 35 it will be observed that the pressure-gage G is placed in communication with the passageway 10 between the valve I and the point at which said passageway communicates with the chamber b; that the pressure-gage H is placed in communication with said passageway between said valve and the air-receiving 40 end of the hose; that when upon closing the valve I and opening the valve f air under pressure is pumped into the chamber b through the trunnion E air under pressure is stored within said chamber and the drum 45 B therefore constitutes a compressed air-reservoir as well as a hose-winding drum; that air under pressure passes from the chamber b upon opening the valve I through the passageway 10 into the hose C; that by 50 having the valve 14 of the nozzle 13 closed preparatory to the passage of air from the passageway 10 into the hose air under pressure is stored within the hose from end to end of the hose; that the hose is inflated by 55 supplying it with air under pressure and kept inflated so long as the valve of the nozzle 14 remains closed. Of course as soon as the hose is sufficiently inflated to render it stiff enough to prevent liability of the 60 hose to collapse or readily bend the valve I is closed.

The pressure-gage G is used in indicating the pressure to be maintained within the chamber b. The pressure-gage H is em-

ployed in indicating the pressure to be 65 maintained within the hose. Whenever the pressure-gage G indicates a reduction of air pressure within the chamber b below the pressure to be maintained in said chamber an air-pump (not shown) is placed in 70 communication with the bore e in the trunnion E and operated upon opening the valve f to reestablish the air-pressure to be maintained within said chamber whereupon said valve is closed. Of course the air stored 75 within the chamber b is under a greater pressure than the air under pressure supplied to the hose, and whenever the pressure-gage H indicates less air-pressure in the hose than ought to be maintained in 80 the hose when the hose is not in use the valve I is opened to permit additional air under pressure to pass into the hose but closed as soon as said gage indicates that the requisite air-pressure has been established within the 85 hose.

By the construction hereinbefore described it will be observed that the winding drum B and the circumferentially extending rails 8 form a hose-reel which comprises a compressed-air-reservoir arranged concentrically 90 relative to the axis of the reel between the ends of the reel; that said reservoir participates in the formation of the body of the reel and is arranged and contoured to form 95 said winding drum; that said reel takes up no more room than the ordinary reel which does not comprise said reservoir; that the reel comprising said reservoir is provided with a circumferentially extending passageway which is continually in communication 100 with said reservoir; that a pressure-gage is placed in communication with said passageway and adapted to indicate the air-pressure to be confined in the hose when the hose 105 is not in use; and that the valve which controls communication through said passageway is arranged between the point at which said pressure-gage is placed in communication with the passageway and the point at 110 which said passageway is placed in communication with the aforesaid reservoir.

What I claim is:—

1. In a fire-hose-cart, a suitably supported winding drum having an interior chamber 111 in which air under pressure is to be stored, which chamber is provided at the axis of the drum with a valved air-inlet, said drum being provided externally of said chamber with a passageway extending circumferentially of the drum, which passageway communicates at one end with said chamber and is adapted to communicate at its opposite end with a fire-hose; two pressure-gages placed in communication with said passageway at points spaced longitudinally of the passageway between the last-mentioned end of the passageway and the point where the

passageway communicates with the aforesaid chamber, and a valve controlling communication through said passageway between the points at which the pressure-gages are placed in communication with the passageway.

2. In a fire-hose-cart, a hose-reel comprising a compressed-air-reservoir and provided externally with a passageway which 10 extends circumferentially of the reel and communicates with said reservoir and is adapted to conduct air from said reservoir to a fire-hose; a pressure-gage placed in communication with said passageway and adapted to indicate the pressure of air confined in the fire-hose, and a valve controlling communication through said passageway and arranged between said pressure-gage and the point at which said passageway is 15 placed in communication with the aforesaid reservoir, said reservoir participating in the formation of the body of the reel.

3. In a fire-hose-cart, a hose-reel comprising a compressed-air-reservoir and provided 25 externally with a passageway which communicates with said reservoir and is adapted to conduct air from said reservoir to a fire-hose; a pressure-gage placed in communication with said passageway and adapted to indicate the pressure of air confined in the fire-hose, and a valve controlling communication through said passageway and arranged between said pressure-gage and the point at which said passageway is 30 placed in communication with the aforesaid reservoir, said reservoir participating in the formation of the body of the reel and being arranged concentrically relative to the axis of the reel.

40 4. In a fire-hose-cart, a hose-reel comprising a compressed-air-reservoir and provided externally with a passageway which communicates with said reservoir and is adapted to conduct air from said reservoir to a fire-hose; a pressure-gage placed in communication with said passageway and adapted to indicate the pressure of air confined in the fire-hose, and a valve controlling communication through said passageway and arranged between said pressure-gage and the point at which said passageway is placed in communication with the aforesaid reservoir, said reservoir being arranged and contoured to form a winding 45 drum for fire-hose.

5. In a fire-hose-cart, a hose-reel comprising a compressed-air-reservoir provided at its circumference with a passageway adapted to conduct air to a fire-hose; a 50 pressure-gage placed in communication with said passageway and adapted to indicate the air-pressure in the fire-hose, and a valve controlling communication through said passageway and arranged between the point

at which said pressure-gage is placed in 65 communication with the passageway and the air-inlet of the passageway, the aforesaid reservoir being placed in communication with said passageway through the aforesaid air-inlet and provided with two suitably supported trunnions arranged at opposite ends respectively of the reel and in line endwise, one trunnion being provided 70 interiorly with a valved bore forming the air-inlet of the reservoir.

6. In a fire-hose-cart, a hose-reel provided externally with two suitably supported trunnions arranged at opposite ends respectively of the reel and in line endwise, one trunnion being provided interiorly with a 75 valved bore, said reel being provided with a passageway which is in communication with the aforesaid bore and adapted to conduct air to a fire-hose; two pressure-gages placed in communication with said passageway at points spaced between the point at which the passageway is adapted to connect with a fire-hose and the air-inlet of the passageway, and a valve controlling communication through said passageway and arranged between the points at which said pressure-gages are placed in communication with the passageway.

7. In a fire-hose-cart, a hose-reel comprising a compressed air-reservoir provided externally with two suitably supported trunnions arranged at opposite ends respectively of the reel and in line endwise, one trunnion being provided interiorly with a valved bore, communicating with said reservoir, said reel being provided at its circumference with a passageway which is placed in communication with said reservoir and adapted to conduct air to a fire-hose; two pressure-gages placed in communication with said passageway at points spaced between the point at which the passageway is adapted to connect with a fire-hose and the point at which the passageway is placed in communication with said reservoir, and a valve controlling communication through said passageway and arranged between the points at which said pressure-gages are placed in communication with the passageway.

8. In a fire-hose-cart, a winding drum provided exteriorly with two suitably supported trunnions arranged at opposite ends respectively of the drum and in line endwise, one trunnion being provided interiorly with a valved bore, said drum being provided with a passageway arranged at the periphery of the drum, which passageway is in communication with the aforesaid bore and adapted to conduct fluid received thereby to a fire-hose; two pressure-gages placed in communication with said passageway at points spaced between the point at which

the passageway is adapted to connect with a fire-hose and the air-inlet of the passageway, and a valve controlling communication through said passageway and arranged between the points at which said pressure-gages are placed in communication with the passageway.

Copies of this patent may be obtained for five cents each, by addressing the "Commissioner of Patents, Washington, D. C."

In testimony whereof, I sign the foregoing specification, in the presence of two witnesses.
